UNITED STATES PATENT OFFICE

RALPH FORBUSH NORRIS, OF MADISON, WISCONSIN, ASSIGNOR TO C. F. BURGESS LABORATORIES, INC., OF MADISON, WISCONSIN, A CORPORATION OF DELAWARE

ACOUSTICAL STUDY AND CORRECTION OF AUDITORIUMS

Application filed April 13, 1927. Serial No. 183,343.

My invention relates generally to the acoustical study and correction of rooms, such as theaters, churches, or other auditoriums, and has particular reference to the control or 5 elimination of echoes in such rooms.

One of the objects of my invention is to provide a means for showing and determining which surfaces of a room, either proposed or existing, cause echoes.

10 Another object of my invention is to provide a means for showing and determining the direction or directions in which sound is traveling at predetermined given points in rooms, such as theaters, churches, or other 15 auditoriums.

Another object is to make a record, as by photography, of the sound paths and sound concentrations in rooms.

Sound waves consist of a traveling succession of relatively high and low pressure areas. These areas move forward in air at approximately 1088 feet per second at ordinary room temperatures. When these waves strike a comparatively smooth and non-porous surface, they are reflected from it. As 20 with light waves, if the sound wave strikes a reflecting surface in a direction normal to its plane, it is reflected back toward its source.

If the wave strikes the surface at an angle, it 25 is reflected from the surface at the same angle. After a sound wave has been generated in a room, it is reflected from surface to surface, producing an enormously intricate sound pattern in the room. The laws of sound reflection 30 are like those of light, and every surface that the sound strikes may be considered, in some respects, as a secondary source of sound. As a mirror absorbs some of the light that falls upon it, so surfaces struck by sound 35

waves absorb a portion of the energy in the waves, the percentage being dependent upon the nature of the surface. The result is that the reflected sound in a room becomes continually weaker as its energy is partially absorbed by the successive reflecting surfaces.

40 The length of time that it takes for a sound of standard intensity to be so reduced by absorption that it becomes inaudible, is called the period of reverberation of the room.

45 50 An echo is closely related to reverberation.

The human ear is so constituted that it cannot distinguish two sounds less than one-fifteenth of a second apart as two sounds, but receives them as one prolonged sound. If the sounds are more than one-fifteenth of a second apart, they are heard by the ear as two distinct sounds.

Sound travels about 1088 feet per second under ordinary room temperature conditions, so that if a sound generated at a given point 55 can reach the auditor's ear over two paths whose lengths differ by one-fifteenth of 1088 feet, or approximately 72 feet, the sound will reach the ear of the auditor as two distinct sounds 1/15 of a second apart. When this 60 occurs, the sound wave reaching the ear latest is called an echo. When the difference in the length of the two paths is more than 72 feet, the echo will follow the direct sound by a time interval even greater than 1/15 of a 65 second. When one or more echoes are produced in a room, a confusion of sounds results and the room is described as having "poor acoustics." My invention is directed to 70 means for determining those surfaces which 75 produce "confusion echoes."

The usual method now employed for finding echo-producing surfaces in rooms is graphical. In using this method it is necessary to construct scale drawings of cross-sections of the room, to lay out "rays" of sound directly from the source of sound, and indirectly as reflected from smooth nonabsorbent surfaces, making the angle of reflection of the sound ray equal to the angle of incidence. 80 In this way, a series of lines may be built up which will show the sound paths and areas of sound concentration. Echoes may be detected by determining the difference in the lengths of the respective paths by which sound will 85 travel from the source to any given point in the room, an echo being produced when the difference in the paths is, roughly, 70 feet or more. This method is very laborious and less accurate than my improved method.

90 The present invention dispenses with the graphical effects and substitutes visual effects which may be produced instantaneously and varied at will. The new method providing visual effects is capable of retaining 100

all the advantages of the graphical method upon photographing the visual effect.

In carrying out my invention, I utilize the similarity as to reflection between sound and light waves. However, the high speed with which light travels (187,000 miles per second) and the ease with which light rays may be photographed, as, for example, by allowing them to act on sensitized paper, or by photographing a surface illuminated by the light rays, make it decidedly advantageous to use light rays in determining the acoustics of a room. This will be explained more in detail hereinafter. It is possible to photograph the effect of sound waves or pulses but such photographs only show the momentary curvature or contour of the wave front. By taking a succession of photographs, the changing contour of a sound wave may be shown as it strikes obstructions, such as surfaces, or as it interferes with other sound waves, or where it is reflected by surfaces. During the period that the wave front is relatively simple in form, this method may give satisfactory results, but when the sound wave is broken up by striking various obstructions it becomes difficult to obtain satisfactory results (see *Acoustics in auditorium design* by P. E. Sabine in *American Architect*, June 18, 1924). In this method a small model of a room is erected and successive photographs of a single sound wave emanating from the designated source of sound (such as the stage in a theater) are made. This method is very cumbersome and requires a highly developed technique. It has the further disadvantage that it shows the progress of a single wave only, whereas sound is composed of a rapid succession of waves which will often create acoustic conditions differing widely from the pictures of the single wave.

In my improved method, I replace the sound waves emanating from the designated sound source by light rays. I am often able to obtain complete information about the echo-producing surfaces of a room or auditorium in one picture or photograph, and nearly always in three or four. I not only locate the source of the loudest echoes, but I also locate the source of secondary echoes, and I am also able to show visually the direction and intensity of sound at any predetermined point in a room. My method instantaneously shows the sound pattern produced by a multiplicity of sound waves rather than that produced by a single wave front, and therefore shows the normal condition in a room, with the utmost simplicity.

The claims of this application are directed to the apparatus for attaining the results enumerated. In the divisional application No. 332,118, filed January 12, 1929, which issued August 27, 1929, as Patent No. 1,726,-

I also included claims directed to a species. Another divisional application No. 357,285 filed April 22, 1929, which issued August 27, 1929, as Patent No. 1,726,501 contains method claims directed to another species. 70

In the accompanying drawings—

Figure 1 illustrates a photo-picture made by my process which shows the acoustics of a room, such as a theater auditorium having echoes. 75

Fig. 2 illustrates a photo-picture of the improved acoustics of the theater of Fig. 1, after being corrected acoustically.

Fig. 3 shows one form of apparatus used in carrying out my invention. 80

By way of illustration in the preferred manner of carrying out my invention, I first make contours of a room, utilizing both plan views and various horizontal or vertical cross-sections, depending upon the particular problem under consideration. These miniature contours may preferably be from 12 to 24 inches long, but must be faithful reproductions as to the form of the original. When the contour has been reproduced on paper or 90 cardboard, or in other convenient form, a strip of polished metal or other reflecting material, about one to two inches wide, is erected on edge along the plane contour of the room, providing a fence-like contour that 95 may be considered as a slice-section of the auditorium. The fence may be a single strip, or a number of sections. In Fig. 3, the characteristic portions of the fence are designated by the numerals 1, 2, 3, 4 and 5. It is usually 100 unnecessary to erect a strip for the floor of the room, as I have done at 6, since the audience is on the floor. The audience, together with the seats and carpets, are excellent absorbers of sound and therefore a light-reflecting surface does not represent the true condition. 105

Accordingly, in Fig. 3, the strip 6 is not light-reflecting. It therefore becomes necessary to know the types of surfaces in the room in order to duplicate exactly the conditions in 110 miniature. Surfaces vary in their ability to absorb sound, as is well known to those skilled in the art. Since continuous smooth surfaces are good reflectors of sound and are potential sources of echoes, I simulate these surfaces 115 in the miniature contour by leaving the corresponding areas of the reflecting strip polished. The areas which are sound-absorbing are treated so that they do not reflect light, or these sections of the contour strip may be 120 entirely omitted. Occasionally, it only becomes necessary to erect the contour of the ceiling in miniature, since the ceiling is sometimes the only portion having sound-reflecting areas. Side walls may also be sources of 125 echoes. If the room under consideration is the auditorium of a theater, as shown in Fig. 3, there may be a balcony 7, which must be inserted for reasons which will become apparent. The source of sound is considered to 130

be on the stage 8. A small light 9, preferably an incandescent bulb, is placed at this point.

In one application of my invention, after the miniature contour fence is completed, it may be slipped over a sensitized surface, such as a sheet of photographic paper, the strips of polished metal or other reflecting or treated surface forming the contour being at right angles to the sensitized surface. This operation is of necessity carried out in a dark room, or in properly subdued light. The light 9, if an incandescent bulb, should have a concentrated filament and should be placed so as to illuminate both the contour strip 15 and the entire sensitized surface which corresponds to the area traversed by the sound. This light, being connected to a suitable source of electrical energy, is then flashed. The intensity or length of flash should be such 20 that any concentrations of light which are caused by the curvature or angle of the metal wall will stand out in contrast to the balance of the sensitized surface. These concentrations of light closely approximate the concentrations of sound in the auditorium. The exposed sensitized surface may then be developed or otherwise treated to fix the image permanently, as in a photo-print.

In another modification of my process, instead of placing the contour strip on a sensitized surface, I erect it on any uniformly colored plane surface. The light at the point of sound emanation is turned on. The plane surface is illuminated in varying intensity, 35 in proportion to the concentration of sound. This allows the acoustics of the room to be studied, so that the observer may treat the reflecting surfaces, or carry out other ideas and observe immediately the effect of such 40 treatments. Instead of replacing the plane surface with a sensitized surface, as herein-before described, the plane surface may be photographed directly by any suitable apparatus in the usual way. Any number of 45 photo-prints may then be made from the negative obtained in this way, the areas of light concentration being light instead of dark, as in the process where the contour is mounted on the sensitized surface.

50 When it is desired to know in what direction sound is traveling at definite points, as 10 to 29, throughout the room or auditorium, pins, needles, pegs, or similar articles, herein-after called pins, may be inserted at these 55 points of the surface on which the contour is erected. It is especially desirable to know the source of sound at the points where the audience is located. The pins cast shadows, as shown in Figs. 1 and 2 by dotted lines of 60 which the spacing increases as the shadow fades out. The intense end of a shadow points in the direction of the light source, either direct or reflected. In this way, it is often found that at some points in a room, as in 65 Fig. 1, the audience hears the sound from as

many as five points at one time, one sound slightly after the other. This causes a series of disturbing echoes or reverberations, resulting in poor acoustics. Once the reflecting surface is found, it is a simple matter to 70 apply a highly absorbent acoustical material to it, as is understood by those skilled in the art.

Fig. 1 illustrates the appearance of a photo-picture made by my method. The picture 75 is cut in the form of the contour. It is the sound pattern obtained for a theater having poor acoustics. In the miniature, or slice model, the light was placed at 9 on the stage 8. The print shows that the ceiling curvature 80 at 1 causes echoes in the audience at 12, 13, 14, 15, 16 and 17. The pins inserted at these points show that the sound will be heard principally from two points, the stage 8 and the curved surface 1. Since the distance from 85 the stage to the curved surface and back to points 12 to 17 is more than 72 feet greater than the direct distance from the stage, the curved surface produces bad echoes for the audience, especially in the region from 90 12 to 17. The curved surface 2 also causes some echo at 16, 17 and 18, making the acoustics very poor at 16 and 17. At 18 sound is also heard reflected from section 3' of curved surface 3. Section 3 also reflects the sound into 95 the rear of the balcony, at 22, thereby re-enforcing the sound. This re-enforcement betters the acoustics at 22, since the length of the longer sound path is less than 72 feet more than the length of the direct path. Fig. 2 100 shows a photo-picture of the acoustics of the same theater after sound absorbing materials 30, 31 and 32 were installed on the echo producing sections of curved surfaces 1, 2 and 3. The echoes are completely eliminated and the 105 audience on the lower floor hears the sound from only one source, the stage.

As an example in studying the acoustics of an auditorium, it is customary to take one picture of the reflection of the side walls on 110 the floor plan; another picture of the reflection through the longitudinal section of the room; and a third picture on the transverse section of the room. In this way all of the concentrations which cause echoes can be detected, together with the surfaces from which they emanate. In the case of new buildings, the angles and curvatures of the surface may be changed to eliminate these echoes, but in the case of buildings already constructed, sound-absorbing material may be placed on 115 these surfaces in such a way as to eliminate the echoing effect.

Various departures from and modifications of the method and apparatus herein described are, of course, contemplated. In the foregoing example, the reflection of light rays proper have been employed to indicate the course of sound by relative intensities of the light. It will be observed that in Fig. 2, the 120 125 130

pin 24 casts a shadow 24^a which is reflected forwardly as a shadow 24^b by the rear wall 5. Thus, a beam of light or a shadow may be employed and its reflection studied.

What I claim as new is:

5. 1. An apparatus for showing the paths and intensity of sound waves from a given source in a room, comprising a plane surface on which is mounted a miniature fence-like member having the contour of a cross-section of said room, in combination with a source of light positioned at a point corresponding to the point of sound emanation in said room.
10. 2. An apparatus for showing the paths and intensity of echo-producing surfaces in a room, comprising, in combination a plane surface, a fence-like member having the contour of the section of sound reflecting areas in said room on a small scale, mounted on said plane surface, and a source of light positioned at a point corresponding to the point of sound emanation in said room.
15. 3. An apparatus for photographing the paths and intensity of sound waves from a given source in a room, comprising a plane surface on which is mounted a miniature fence-like member having the contour of a cross-section of said room, in combination with a source of light positioned at a point corresponding to the point of sound emanation in said room, and means to record the light intensities on said plane surface.
20. 4. An apparatus for picturing the paths and intensity of sound waves from a given source in a room, comprising in combination a sensitized surface, a miniature light-reflecting fence-like member having the contour of a cross-section of said room adapted to be mounted on said surface, and a source of light positioned at a point corresponding to the point of sound emanation in said room.
25. 5. An apparatus for picturing the paths and intensity of sound waves from a given source in a room, comprising in combination, a sheet of sensitized paper, a regulable reflecting metal fence-like miniature member having the contour of a cross-section of said room, and an incandescent bulb positioned at a point corresponding to the point of sound emanation in said room.
30. 6. An apparatus for picturing the paths and intensity of sound waves from a given source in a room, comprising a plane surface on which is mounted a miniature fence-like member having the contour of a cross-section of said room, in combination with a source of light positioned at a point corresponding to the point of sound emanation in said room, said contour surface in light-reflecting properties simulating the sound-absorbing properties of the corresponding surfaces of said room.
35. 7. An apparatus for picturing the paths and intensity of sound waves from a given source in a room, comprising a sheet of sen-
- sitized paper on which is mounted a polished metal reflecting-strip providing a miniature member having the contour of a cross-section of said room, in combination with an electric incandescent bulb positioned at a point corresponding to the point of sound emanation in said room, said reflecting strip surface having been treated as to its light-reflecting surface to simulate the sound-absorbing properties of the corresponding surfaces of said room.
40. 8. In apparatus for picturing the paths and intensity of sound waves from a given source in a room, a miniature light-reflecting contour wall representing a portion of a cross-section of said room and obstructions to light positioned therein to throw shadows and indicate the reflections of light from said wall.
45. 9. In apparatus for picturing the paths and intensity of sound waves from a given source in a room, a reflecting strip providing a miniature fence-like member having the contour of a portion of a cross-section of said room, said reflecting-strip surface having been treated on its light-reflecting surface to simulate the sound-absorbing properties of the corresponding surfaces of said room.
50. 10. In apparatus for picturing the paths and intensity of sound waves from a given source in a room, miniature cross-sectional fence-like contour sections of sound-reflecting surfaces of said room, said miniature sections being treated to simulate the sound-reflecting properties of the corresponding sections of said room.
55. 11. Means for studying the acoustic properties of an auditorium, which comprises in combination a miniature slice-section of the auditorium, and a source of light as a representation of a source of sound, the sound-reflecting surfaces of the auditorium being represented in the miniature section by light-reflecting surfaces.
60. 12. Means for studying the acoustic properties of an auditorium, which comprises in combination a miniature slice-section of the auditorium, a source of light as a representation of a source of sound, the sound-reflecting surfaces of the auditorium being represented in the miniature section by light-reflecting surfaces, and means for recording the relative intensities of light throughout the area of the section.
65. 13. Means for studying the acoustic properties of an auditorium, which comprises in combination a sheet of light-sensitive material, a miniature slice-section of the auditorium placed upon said sheet, and a source of light as a representation of a source of sound, the sound-reflecting surfaces of the auditorium walls being represented in the miniature by light-reflecting surfaces.
70. 14. Means for studying the acoustic properties of an auditorium, which comprises in

combination a sheet or light-sensitive material, a miniature slice-section of the auditorium placed upon said sheet, and light-obstructing pins at particular points in the miniature to indicate by their shadows the direction of light.

In testimony whereof, I have subscribed my name.

RALPH FORBUSH NORRIS.
